UNITED STATES PATENT OFFICE.

PETER W. SPRECHER, OF MILWAUKEE, WISCONSIN.

ELECTRIC-LIGHTING FIXTURE.

1,385,192.

Specification of Letters Patent.

Patented July 19, 1921.

Application filed March 1, 1920. Serial No. 362,369.

To all whom it may concern:

Be it known that I, PETER W. SPRECHER, a citizen of the United States, and resident of Milwaukee, in the county of Milwaukee and State of Wisconsin, have invented certain new and useful Improvements in Electric-Lighting Fixtures; and I do hereby declare that the following is a full, clear, and exact description thereof.

10 This invention pertains to new and useful improvements in electric lighting fixtures, and relates particularly to an improved means for insulatingly mounting the canopy of such fixtures.

15 In my Patent No. 1,154,070, issued to me Sept. 21, 1915, I illustrate an improved type of lighting fixture in which the current distribution wires pass through the canopy at the extremity thereof. The primary object 20 of the present invention is to provide a lighting fixture somewhat similar to that depicted in this patent but having an improved arrangement of parts whereby the current distribution wires may be disposed 25 through the side walls of the canopy.

Another object of the invention is to provide a simply constructed and efficient means for mounting a lighting fixture canopy upon a wall or ceiling in such a manner that the attaching means will be thoroughly insulated.

30 With these general objects in view, the invention resides in the novel features of construction, combination and arrangement 35 of parts which will be hereinafter more particularly described and claimed and shown in the drawing forming a part thereof, wherein—

40 Figure 1 represents a part elevational and part sectional view of an electric lighting fixture constructed in accordance with the invention.

45 Fig. 2 is a detail transverse sectional view taken on the plane of the line 2—2 of Fig. 1. In the accompanying drawing I have illustrated a portion of a ceiling or wall 1 as having a nipple 2 extended therefrom, the nipple being exteriorly screw threaded and adapted to form one portion of an attaching 50 means for mounting a canopy 3 of suitable design. In the present instance this canopy 3 is provided on opposite sides with

rings 4 by which suspending chains (not shown) may be attached thereto. The extremity of the canopy has an opening 5 receiving a block 6 which forms one element of a canopy attaching means. 55

This block 6 is preferably of indurated fiber or other insulating material and is shouldered as at 7 and provided with a central bore 8. The inner portion of the block is counter-bored to receive one end of an insulating sleeve 9 through which and the bore 8 a suspending screw 10 is extended.

65 The head of said screw engages the outer end of the block 6 and the inner screw threaded end is threaded into an aperture formed in one side of an attaching yoke 11. The opposite side of the yoke 11 is provided 70 with a screw threaded socket 12 adapted to receive the threaded end of the nipple 2, the free end of which nipple seats against the bottom of the socket as shown in Fig. 1. The intermediate portion of the yoke forms 75 a ringlike member by which the yoke may be readily threaded upon the nipple 2, it being obvious that a suitable tool may be inserted in the opening thereof.

80 Current distribution wires 13 extend from the ceiling 1 within the canopy 3 and are adapted to be extended through the side wall thereof. In the present instance the ring base 14 of one of the rings 4 is apertured to receive the wires 13. As a result of 85 this arrangement the canopy 3 is effectively mounted and insulated from its attaching means although the distribution wires 13 extend through the side wall of said canopy rather than through the insulating block 6 90 as in the case of the structure illustrated in my patent above referred to.

95 Various changes may be made in the form and proportion and in the general association of the different parts of the fixture without departing from or sacrificing any of the advantages thereof.

I claim:

An electric lighting fixture comprising an attaching yoke composed entirely of metal 100 and having a threaded aperture at one end, an internally threaded socket at the other end of the yoke for receiving the threaded end of a gas pipe, the bottom of the socket

being adapted to close the end of the pipe, a canopy disposed over the yoke and having an opening in its extremity, an insulating block in said opening and having a bore, an attaching screw disposed through the bore of the block and threaded in the aperture of the yoke, and an insulating sleeve surrounding the screw, said canopy being provided

with uninsulated openings in its sides for the current distribution wires.

In testimony that I claim the foregoing I have hereunto set my hand at Milwaukee, in the county of Milwaukee and State of Wisconsin.

PETER W. SPRECHER.
